UNITED STATES PATENT OFFICE.

FRANCIS J. STOKES, OF PHILADELPHIA, PENNSYLVANIA.

STILL.

No. 861,485.

Specification of Letters Patent.

Patented July 30, 1907.

Application filed December 11, 1906. Serial No. 347,298.

To all whom it may concern:

Be it known that I, FRANCIS J. STOKES, a citizen of the United States, and a resident of Philadelphia, in the county of Philadelphia and State of Pennsylvania, 5 have invented a certain new and useful Still, of which the following is a specification.

Objects of the present invention are to provide a still which shall be simple in construction and reliable in operation and adapted especially for supplying distilled water for hospital, domestic and other uses; to so 10 construct and arrange the parts of the still that gases and vapors may escape and be driven from the raw water or water which is to be purified by distillation; and to permit of the proper overflow of condensing water and at 15 the same time maintain a supply of feed water exposed to the air and in position for securing the maximum quantity of heat from the distilled water, whereby the feed water is highly heated, vapors and gases are expelled therefrom, and material economy and efficiency 20 in operation attained.

To these and other ends hereinafter set forth the invention comprises the improvements to be presently described and finally claimed.

In the accompanying drawings, Figure 1, is a central 25 sectional view of a still embodying features of the invention showing one of the three arms in section and one in elevation, the third being absent from the view because it is a sectional view, and Fig. 2, is a sectional view illustrating a section of the arm which is shown in elevation in Fig. 1, that is, the arm 14.

In the drawings 1, is a tubular casing having a discharge outlet 2, at its bottom and into the base of which raw water is introduced as at 3. This casing is open at its top, as at 4, for the escape of gases and vapors from 35 the raw water into the air prior to the introduction of the water into the boiler. The casing 1, is shown as supported by means of a bracket 5, which may be secured to the wall 6. However, the casing may obviously be supported by other means and while it is 40 shown as of circular cross-section, such shape is not essential, though no doubt preferable.

7, is a boiler having a concavity 8, in its base arranged co-axially above the open end 4, of the casing. In the bottom of the concavity is an opening as at 9, leaving 45 an inturned annular flange.

10, is a heating coil through which the heating medium may be caused to circulate by way of the connections 11 and 12.

13, and 14, designate arms having spaces between 50 them and extending from the casing 1, to the boiler. In the device illustrated in the drawings there are three such arms, although only two of them shown in the drawings and the existence of the spaces between them affords egress for the vapors and gases that are expelled 55 at the open top of the casing 1.

15, is a feed connection from the top of the casing 1,

to the bottom of the boiler. In the apparatus shown in the drawings, it is formed through the arm 13.

16, is an overflow connection from the casing beneath the top thereof to above the water line of the boiler and 60 thence downward to a suitable connection 17. This overflow connection is shown as formed through the arm 14 and vented as at a.

18, are condensing tubes projecting above into the boiler and sealed at the places where they pass through 65 a tube plate 19, that rests on top of the concavity 8, or perhaps more properly on the flange at the top of the concavity.

20, is a tube plate near the bottom of the casing 1, and through which the tubes are sealed. 70

In use raw water rises through the casing 1 and in doing so is heated by the heat from the steam which is condensed in descending through the tubes 18. The excess of raw water escapes through the overflow connection 16, which by reason of its rise or hump fixes 75 the level of the water in the boiler, carries off any surplus and draws the surplus from a point suitably below the top of the casing 1, so that there is maintained at the top of the casing 1, a zone or region of boiling water. Hot water from this zone or region is led by 80 way of the feed connection 15, to supply the boiler and as has been already intimated gases or vapors, which escape from the hot water at the top of the casing 1, pass away from the apparatus through the space between the top of the casing 1, and the walls of the concavity of the boiler and past the supporting arms. The inverted U-shaped overflow 16, communicates with the feed water space below the top of the casing, so that the overflow escapes from below the top of the casing; thus there remains a supply of water above the 90 entrance to the overflow and this water is highly heated and drawn upon to feed the still by way of the passage 15. From this highly heated water vapors escape at the open end of the casing 1, into the concavity 8, and from the concavity they may descend 95 between the arms 13 and 14, and the arm not shown.

Obviously changes may be made in details of construction within the language of the claims so that the invention is not limited to the precise details of construction and arrangement illustrated and above described, but 100

What I claim is

1. A distilling apparatus comprising a tubular casing having a discharge outlet at its bottom and into the base of which raw water is admitted and which is open to the air at its top for the escape of gases from the water, a boiler having a concavity in its base arranged co-axially above the open end of the casing affording space between the boiler and the top of the casing for the escape of the gases, arms having spaces between them and extending from the casing to the boiler, a feed connection from the top of the casing to the boiler, an overflow connection from the casing beneath the top thereof to above the water line in the boiler whereby a zone of hot water is 105 110

maintained for the feed supply, steam condensing tubes projecting into the boiler and sealed through the top of the concavity, and a tube plate near the bottom of the casing and through which the tubes are sealed, substantially as described.

2. A distilling apparatus comprising a casing having a discharge outlet at its bottom and into the base of which raw water is admitted and which is open at its top for the escape of gases from the water, a boiler arranged above the 10 open end of the casing, arms having spaces between them and extending from the casing to the boiler to support the former clear of the latter, a feed connection from the casing to the boiler, an overflow connection from the casing, condensing tubes projecting from above the open top of 15 the casing and penetrating the boiler, and a tube plate near the bottom of the casing and through which the tubes are sealed, substantially as described.

3. A distilling apparatus comprising a casing having a discharge outlet at its bottom and into the base of which raw water is admitted and which is open at its top for the 20 escape of gases and vapors, a boiler arranged co-axially above the open end of the casing, arms extending from the casing to the boiler and of which one has formed in it a

feed connection and another has formed in it an overflow connection, condensing tubes projecting above the end of 25 the casing into the boiler, and a tube plate near the bottom of the casing and through which the tubes are sealed, substantially as described.

4. A distilling apparatus comprising a tubular casing having a discharge outlet at its bottom and into the base 30 of which raw water is admitted and which is open at its top for the escape of gases, a boiler having a concavity in its base which is provided with an opening, arms extending from the casing to the boiler, a feed connection from the casing to the boiler, an overflow connection from the 35 casing, a tube plate arranged in the boiler over the opening in the concavity, condensing tubes sealed through said tube plate, and a tube plate near the bottom of the casing through which the tubes are sealed, substantially as described.

In testimony whereof I have hereunto signed my name.

FRANCIS J. STOKES.
